UNITED STATES PATENT OFFICE.

TIMOTHY J. KIELEY, OF NEW YORK, N. Y.

STEAM-HEATING SYSTEM.

SPECIFICATION forming part of Letters Patent No. 391,415, dated October 23, 1888.

Application filed September 4, 1885. Serial No. 176,194. (No model.)

To all whom it may concern:

Be it known that I, TIMOTHY J. KIELEY, of the city, county, and State of New York, have invented a new and useful Improvement in 5 Steam-Heating Systems, of which the following is a full, true, and exact description, reference being had to the accompanying drawings.

This invention relates to an improved apparatus by means of which the water is automatically returned to the boiler from a steam-heating system and the level of the water in the boiler constantly maintained. By this system, likewise, the effect known as "hammering" in the pipes is to a great degree prevented. That which is new in my invention will be found specified in the claims annexed to this specification.

My invention will be readily understood from the accompanying drawings, in which— 20 Figure 1 represents a view of my entire system; Fig. 2, a detailed view of the pump-regulating governor.

A represents the boiler or source of steam. The steam from this boiler passes through the 25 main steam-pipe F to the different parts of the heating system. For instance, the radiator E and the box-coils E' E are connected with such main steam-supply in this pipe. At T is placed a pressure-regulating valve of one of the known 30 forms, which determines the pressure existing beyond it in the system. The returns from the heating-coils connect with a main return-pipe, N. Such connections are shown at M and O. In some pipe connecting the steam- 35 supply and the return distant from the boiler I locate a water-gage, V, for a purpose herein-after to be determined. The main return-pipe connects with a pump-governor, C, which may be of any known form, though I prefer the 40 form shown in Fig. 2. The connection is made through the single pipe N'.

It will be readily seen that the single connection thus shown performs a valuable function over two connections in the following particu- 45 lar: If a connection entered the pump-governor chamber and the water passed into that pump-governor chamber through said connection and left it through another, there would necessarily be a continued flow of the water 50 of condensation through that pump-governor, whereas by the single connection shown the

water will fall and rise in the pump-governor without substantially changing. By means of the single connection shown I am enabled to maintain the pump-governor at a higher tem- 55 perature than would otherwise be possible, and to avoid the continual change of water above referred to. The object of this pump-governor is to determine the action of a pump by the water-supply to the same. The main 60 return-pipe, which connects with the pump D, as shown, connects likewise through the pipe N' with the pump-governor. This pump-governor contains a float, and is connected with a steam-valve in the pipe G, so that when the 65 water rises above a certain level in this pump-governor the steam-pump will commence to operate, thereby forcing the water back to the boiler through the pipe W. Connecting with the main steam-pipe and with the top of the 70 pump-governor is the pipe H, which equalizes the pressure in the pump-governor. The result of this combination is that the water will continually stand in the bottom of the system at about the line *xx*, which prevents 75 the steam from working around back into the radiators by coming down through the connecting-pipe of some other radiator. To this cause is principally due the effect of pound- 80 ing or hammering in the radiators previously referred to. Connecting likewise with the pump-supply is the pipe P, which is connected with the main water-supply to the boiler. In this pipe is the valve R, controlled by the boiler-governor B. This boiler-governor has a 85 float, which, when the boiler-governor is empty of water, causes the valve R to open at its descent, thereby supplying an additional amount of cold water to the pump, which may at that time be operating under the control of the 90 pump-governor. Under these circumstances an additional supply of water will be returned to the boiler in case the pressure in the supply is greater than the pressure in the system. As is generally the case, the inflow of water 95 through the pipe P will set the pump-governor in operation and cause the pump to operate to return the water to the boiler.

The boiler-governor is caused to operate by reason of its connection with the boiler by the 100 pipes S and S'. The bottom of the pipe S dips to the point in the boiler where it is de-

sired to hold the water-level. When the water-level is above the lower end of the pipe S, the boiler-governor will be filled with water and the pipe R closed. If, however, the water drops below this level, the water will also fall out of the boiler-governor and the valve R will be opened.

In some cases I do not employ the pump-governor, but operate the pump by hand. Under these circumstances the engineer, by observing the height of the water in the water-glass V, can determine the height of the seal which he desires to keep in the bottom of the system.

15 It will be observed that the water-glass b is placed in a connection connecting the main steam and return pipes beyond the connection from the radiators nearest to the boiler. This distant water-gage I consider important, as enabling the engineer to regulate his pump-governor by the height of the water at a point distant from the more immediate returns. I find in practice that the distant water-level may be different from that nearer the pump-governor, and it is important for the engineer to regulate the pump-governor by the most distant water-level.

What I claim as my invention, and desire to secure by Letters Patent, is—

30 1. The combination, in a steam-heating system, of a main steam-supply pipe having a regulating-valve therein which automatically governs the main steam-supply pressure, the main return-pipe, the return-pipes from the heating-coils communicating with the said main return-pipe, a pump-governor independent of the main steam-supply, a pump controlled by the said governor, and a steam-connection between the main steam-supply pipe 40 on the low-pressure side of the regulating-valve and the pump-governor, the said connection forming the single connection between the main steam-supply and the pump-governor, substantially as described.

45 2. The combination, in a steam-heating system, of a main steam-supply pipe having a regulating-valve therein which automatically gov-

erns the main steam-supply pressure, the radiators, the main return-pipe, the return-pipes between the radiators and the main return-pipe, a pipe distant from the boiler connecting the steam-supply pipe with the main return-pipe, a gage, V, in the last said pipe, a pump-governor independent of the main steam-supply, a pump controlled by the said governor, and a steam-connection between the main steam-supply pipe on the low-pressure side of the regulating-valve and the pump-governor, the said connection forming the single connection between the main steam-supply 50 and the pump-governor, substantially as described.

3. The combination, in a steam-heating system, of a boiler provided with a boiler-governor and main steam-pipe leading from said boiler, having therein a regulating-valve regulating the pressure of the steam-supply to the system, a pump-governor, a pump, and a steam-connection for operating said pump, a connection between the water-supply and the suction 65 of the pump, and a valve in said connection operated by the boiler-governor, and a connecting-rod connecting said water-valve with the operative parts of the boiler-governor, substantially as described.

4. The combination of a boiler and main steam-supply pipe and regulating-valve placed therein, and steam-heating system supplied from said pipe, and main steam-return, and steam-pump returning the water from 80 said return to the boiler, and pump-governor regulating said pump, the said pump-governor being connected with the return by one connection only, thereby enabling substantially the same water to remain in the pump-governor, and an equalizing-pipe between the pump-governor and the main steam-supply system beyond the equalizing-valve, substantially as described.
